(57) CLAIM

The ornamental design for a wall mounted button panel, as shown and described.

DESCRIPTION

FIG. 1 shows a front elevational view of an embodiment of a wall mounted button panel, with elements in dashed lines forming no part of the claimed design.

FIG. 2 shows an isometric projection of the wall mounted button panel of FIG. 1, with elements in dashed lines forming no part of the claimed design.

FIG. 3 shows a left side elevational view of the wall mounted button panel of FIG. 1, with elements in dashed lines forming no part of the claimed design.

FIG. 4 shows a right side elevational view of the wall mounted button panel of FIG. 1, with elements in dashed lines forming no part of the claimed design.

FIG. 5 shows a top plan view of the wall mounted button panel of FIG. 1, with elements in dashed lines forming no part of the claimed design.

FIG. 6 shows a bottom plan view of the wall mounted button panel of FIG. 1, with elements in dashed lines forming no part of the claimed design.

FIG. 7 shows a front elevational view of another embodiment of a wall mounted button panel, with elements in dashed lines forming no part of the claimed design.

FIG. 8 shows an isometric projection of the wall mounted button panel of FIG. 7, with elements in dashed lines forming no part of the claimed design.

FIG. 9 shows a left side elevational view of the wall mounted button panel of FIG. 7, with elements in dashed lines forming no part of the claimed design.

FIG. 10 shows a right side elevational view of the wall mounted button panel of FIG. 7, with elements in dashed lines forming no part of the claimed design.

FIG. 11 shows a top plan view of the wall mounted button panel of FIG. 7, with elements in dashed lines forming no part of the claimed design.

FIG. 12 shows a bottom plan view of the wall mounted button panel of FIG. 7, with elements in dashed lines forming no part of the claimed design.

FIG. 13 shows a front elevational view of another embodiment of a wall mounted button panel, with elements in dashed lines forming no part of the claimed design.

FIG. 14 shows an isometric projection of the wall mounted button panel of FIG. 13, with elements in dashed lines forming no part of the claimed design.

FIG. 15 shows a left side elevational view of the wall mounted button panel of FIG. 13, with elements in dashed lines forming no part of the claimed design.

FIG. 16 shows a right side elevational view of the wall mounted button panel of FIG. 13, with elements in dashed lines forming no part of the claimed design.

FIG. 17 shows a top plan view of the wall mounted button panel of FIG. 13, with elements in dashed lines forming no part of the claimed design.

FIG. 18 shows a bottom plan view of the wall mounted button panel of FIG. 13, with elements in dashed lines forming no part of the claimed design.

FIG. 19 shows a front elevational view of another embodiment of a wall mounted button panel, with elements in dashed lines forming no part of the claimed design.

FIG. 20 shows an isometric projection of the wall mounted button panel of FIG. 19, with elements in dashed lines forming no part of the claimed design.

FIG. 21 shows a left side elevational view of the wall mounted button panel of FIG. 19, with elements in dashed lines forming no part of the claimed design.

FIG. 22 shows a right side elevational view of the wall mounted button panel of FIG. 19, with elements in dashed lines forming no part of the claimed design.

FIG. 23 shows a top plan view of the wall mounted button panel of FIG. 19, with elements in dashed lines forming no part of the claimed design; and,

FIG. 24 shows a bottom plan view of the wall mounted button panel of FIG. 19, with elements in dashed lines forming no part of the claimed design.
